UNITED STATES PATENT OFFICE

GRIFFIN C. THRIFT, OF HOUSTON, TEXAS

PROPELLER GUARD

Application filed October 4, 1926. Serial No. 139,371.

This invention relates to new and useful improvements in a propeller guard.

One object of the invention is to provide a device of the character described specially designed for use in connection with aeroplane propellers for the purpose of protecting a person while cranking or starting the motor.

With the above and other objects in view 10 this invention has particular relation to certain novel features of construction, arrangement of parts and use, an example of which is given in this specification and illustrated in the accompanying drawings, wherein:—

15 The figure shows a fragmentary sectional view of an aeroplane propeller showing the propeller hub and guard in section.

In the drawing the numeral 1 designates the propeller shaft which is driven from the 20 motor. There is a hub secured to the forward end of this shaft consisting of the annular clamp plates 2 and 3, the former of which is secured to the shaft 1 and the inner ends of the propeller blades 4 are clamped 25 between these plates by the clamp bolts 5, said bolts serving to secure the hub plates 2 and 3 together as well as to secure the propeller blades between said plates. The outer hub plate 3 is formed with a forwardly extending sleeve 6 having the spaced bearing rings 7 and 8 secured therearound. There is a disc-like guard 7 having a central sleeve 9, which rotates around the sleeve 6 and is provided with the internal spaced bearing rings 30 10 and 11, interposed between which and the respective rings 7 and 8 are anti-friction bearings 12. The outer end of the sleeve 9 is provided with an oval enclosing cap 13, thus forming it into a suitable hand rest.

40 When the motor is to be cranked, this is usually done by spinning the propeller and when the motor starts the propeller sets up a strong suction of air toward it which, if the guard 7 is not used, is liable to draw the 45 operator within the range of the rapidly re-

volving blades and he is liable to be injured thereby. When the guard 7 is used the operator, in spinning the blades with one hand, may brace himself by placing the other hand against said hand rest and thus hold himself 50 at all times out of the range of the propeller blades and should the hand slip off the said rest the guard 7 will form a further protection against injury to the operator from said blades.

55 What I claim is:

1. The combination with the propeller of an aeroplane, of a disc-like guard rotatably mounted on the outer end of the hub thereof and a central oval hand rest carried by the outer, or forward, end of said guard, said guard extending outwardly beyond the hand rest on all sides.

2. The combination with a propeller, of a hand rest rotatably mounted on the outer, or forward, end of the hub of the propeller and a flared guard projected from the hand rest.

3. The combination with a propeller, of a hand rest rotatably mounted on the outer, or forward, end of the hub of the propeller and a guard around said hand rest and projecting outwardly therefrom.

4. The combination with the propeller of an aeroplane, of a disc-like guard mounted, 75 on the outer end of the hub thereof and adapted to rotate in either direction independently of the propeller or crank shaft and a central forwardly projecting hand rest carried by said guard.

5. The combination with a propeller, of a hand rest rotatably mounted at the forward end of the hub of the propeller and a disc-like hand guard attached to and surrounding the hand rest.

6. The combination with a propeller mounted upon a revolvable crank shaft, of a hand rest rotatably mounted upon the forward end of the hub of the propeller, said rest comprising a clamp plate secured to the

propeller, said clamp plate having a forwardly extending sleeve, race rings carried by said sleeve, a disc-like guard having a central sleeve which carries race rings adapted 5 to coincide with the first mentioned race rings and anti-friction bearings located between the respective rings of the respective sleeves.

In testimony whereof I have signed my
10 name to this specification.

GRiffin C. THRIFFT.
